UNITED STATES PATENT OFFICE

1,934,515

ELECTROLYTIC CONDENSER

Howard J. Tyzzer, Fort Wayne, Ind., assignor
to Electro Formation, Inc., Fort Wayne, Ind., a
corporation of Ohio

Application May 1, 1931. Serial No. 534,279

4 Claims. (Cl. 175—315)

The present invention relates to electrolytic condensers.

The object of the present invention is to provide a simple, compact, and inexpensive electrolytic condenser which may be easily attached 5 to a panel such as is used in radio receivers.

With this object in view, as will hereinafter appear, the present invention consists of the condenser hereinafter described and particularly defined in the claims.

10 In the accompanying drawing, Fig. 1 is a sectional elevation of what is now considered the preferred form of the invention, and Fig. 2 is an elevation of the invention, illustrating a mode of mounting which insulates the condenser from 15 the panel.

The condenser comprises a filming anode indicated generally at 6, a cathode 8 which serves as a container, and an electrolyte 10 in which the anode is completely immersed. The anode is 20 supported by an anode post 12 which is formed integral with a base 14 which serves as a bottom cover for the container. The cylindrical container 8 is formed with an annular groove 16 which positions the base 14. The base is insulated from the cathode by a flexible rubber gasket 17, the bottom of the container having a spun flange 18 engaging tightly against the gasket, thus holding the anode post securely in place and sealing the bottom of the condenser. 25

30 A perforated lining of celluloid, indicated at 20, protects the anode from accidental contact with the cathode. A vent 22, of any suitable form, is mounted in an indentation 24 at the top of the cathode.

35 A threaded boss 26 under the base 14 of the anode post and integral with it, is adapted to be projected downwardly through a hole in a panel and to be secured in that position by a nut 28 which is of insulating material, such as bakelite. 40 The nut has an upstanding cylindrical sleeve 30 which extends upwardly through the hole in the panel. The nut not only secures the condenser to the panel, but also insulates the boss 26 of the anode post from the panel. A screw 45 34 threaded into the boss 26 provides for attach-

ing the positive connection 36. Contact of the panel and the cathode at 18 provides a grounded negative connection for the condenser if the panel is of metal. If the panel is of insulating material, the negative connection may be made by soldering, as indicated at 38 in Fig. 2. The cathode may be insulated, if desired, from a metal panel by a washer 40 of insulating material, as shown in Fig. 2.

Having thus described the invention, what is claimed is:

1. An electrolytic condenser comprising a filming anode, a cathode which serves as a container, a base of filming material which supports the anode and serves as a bottom cover for the cathode, the base having a depending threaded 70 boss adapted to project through a panel, and a nut of insulating material to engage the threaded boss to hold the condenser securely to the panel.

2. An electrolytic condenser comprising a 75 filming anode, a cathode container for the anode, a base for the anode acting as a cover for the container, the base having a threaded boss to pass through a panel, and a nut of insulating material engaging the boss and having a sleeve 80 to insulate the boss from the panel.

3. An electrolytic condenser comprising a cathode container, a filming anode assembly having a threaded boss adapted to project through a panel, and a base acting as a cover 85 for the container, the cathode having a portion to contact electrically with the panel, and a nut of insulating material engaging the boss and having a sleeve to insulate the boss from the panel.

4. An electrolytic condenser comprising a filming anode, a cathode which serves as a container, a base of filming material which supports the anode and serves as a bottom cover for the cathode, the base having a depending 95 threaded boss adapted to project through a panel, and a nut to engage the threaded boss to hold the condenser securely to the panel.

HOWARD J. TYZZER. 100
